United States Patent Office.

OSCAR I. HARRINGTON AND ELIJAH WEAVER, OF WOOD'S RUN,
PENNSYLVANIA.

Letters Patent No. 94,690, dated September 7, 1869.

IMPROVEMENT IN LEATHER CORD OR ROPE.

The Schedule referred to in these Letters Patent and making part of the same.

To all whom it may concern:

Be it known that we, OSCAR I. HARRINGTON and ELIJAH WEAVER, both of Wood's Run, in the county of Allegheny, and State of Pennsylvania, have invented a new and useful Improvement in "Leather or Skin Cording;" and we do hereby declare that the following is a full, clear, and exact description thereof, reference being had to the accompanying drawings, and to the letters of reference marked thereon.

The nature of our invention consists in making a leather or skin cording, the strands of which are provided with a cotton or hemp "filling."

To enable others skilled in the art to make and use our invention, we will proceed to describe its construction.

In the accompanying drawings, which form part of our specification—

Figure 1 represents a section of the cording, showing filling and wire used for sewing and binding the cord together.

Figure 2 represents a section of the cording, showing the manner of passing the binding wire through the leather or skin.

In the accompanying drawings—

A represents the leather or skin, which is cut in long and narrow strips, the same as used in forming whip-lashes. The width of the leather or skin strips will depend on the size and number of strands used in forming the cord.

B represents the cotton or hemp filling, which is twisted into threads and formed into a cord.

C represents the wire used for binding the twisted strands together. The wire C (which should be annealed so as to be easily bent) is twisted with the strands x x' in the process of twisting the cord, and

should pass through the leather or skin-wrapping, as indicated at s, in fig. 2. The shorter the distance between the points where the wire passes through the leather or skin, the firmer will be the twisted cord. The strips of leather or skin are wrapped around the cotton or hemp filling, after which the strands x x' and the wire C are twisted into cord, as shown in the accompanying drawings.

Cord or rope, made in the manner described, can be manufactured into whip-lashes, fly-nets, traces, bridles, &c., and will be found to be very strong and durable.

In manufacturing the cord for whip-lashes, the use of wire is dispensed with, and the cotton or hemp filling should not be covered or enveloped by the leather or skin-wrapping at the point of the lash, so that the cotton or hemp filling may be formed into the crackle of the lash.

The means and manner of twisting the cord we leave to the skill and judgment of the mechanic.

Having thus described the nature, construction, and advantage of our improvement,

What we claim as of our invention, is—

Leather or skin cording, the strands of which are provided with cotton or hemp filling, as herein described, and for the purpose set forth.

Also, leather or skin cording, the strands of which are provided with cotton or hemp filling, and interwoven with wire, in the manner herein described, and for the purpose set forth.

OSCAR I. HARRINGTON.
ELIJAH WEAVER.
